(57) **CLAIM**

The ornamental design for a bait casting fishing reel, shown and described.

DESCRIPTION

FIG. 1 is a right, front, and top perspective view of a bait casting fishing reel showing my new design;

FIG. 2 is a plan view thereof shown on a reduced scale;

FIG. 3 is a bottom view of FIG. 2;

FIG. 4 is right side elevation view of FIG. 2;

FIG. 5 is a left side elevation view FIG. 2;

FIG. 6 is a rear elevation view of FIG. 2; and,

FIG. 7 is a front elevation view of FIG. 2.

The portions of the drawings shown in dotted lines do not form a part of the claimed design.
